UNITED STATES PATENT OFFICE

113,640

DESIGN FOR A COMBINATION FIELD GLASS AND CASE

Richard Morbee, Chicago, Ill.

Application October 13, 1938, Serial No. 80,426

Term of patent 3½ years

To all whom it may concern:

Be it known that I, Richard Morbee, a citizen of the United States, residing at Chicago, in the county of Cook and State of Illinois, have invented a new, original, and ornamental Design for a Combination Field Glass and Case, of which the following is a specification, reference being had to the accompanying drawing, forming part thereof.

In the drawing:

Figure 1 is a plan view of a combination field glass and case, showing one cover opened and the binoculars adjusted in retracted position;

Fig. 2 is a plan view of the device of Fig. 1, with the cover closed and the binoculars adjusted to open position;

Fig. 3 is an end view showing the covers partially open and the means for focusing the binoculars;

Fig. 4 is an end view opposite to that of Fig. 3 showing the cover partially open; and

Fig. 5 is a side elevational view showing the covers in a partially open position and the binocular in closed position.

I claim:

The ornamental design for a combination field glass and case, as shown and described.

RICHARD MORBEE.
